DOOR LOCK

Stanley Zagrzewski, Chicago, Ill.

Application May 11, 1937, Serial No. 142,038

5 Claims. (Cl. 292—170)

This invention relates to a door lock and has for its object to provide, in a manner as herein-after referred to, a device of the class referred to which may be used as a mortise lock or a rim lock within the door or mounted on its surface.

A further object of the invention is to provide, in a manner as hereinafter set forth, a door lock including a normally active spring controlled latching member and a spring controlled latching member releasing device shiftable in an outward direction in a path at the right to the path of the latching member for releasing the latter.

A further object of the invention is to provide, in a manner as hereinafter set forth, a door lock including a normally active latch member and means slidably engageable with said member and pushed in an outward direction from the inside of the door or pulled from the outside of the door for releasing said member, with only one movement and without any twist or turn.

A further object of the invention is to provide, in a manner as hereinafter set forth, a door lock including a normally active latching member and oppositely slidable releasing means for and engageable with said member whereby in an emergency, as in case of fire, etc. the door is capable of being opened with ease.

A further object of the invention is to provide, in a manner as hereinafter set forth, a door lock including a normally active latching member operated to released position by a sliding element and a normally inactive key operated locking member, and with said members having coacting means to prevent the latching member being shifted to released position when the locking member is in locking position.

Further objects of the invention are to provide, in a manner as hereinafter set forth, a device of the class referred to which is simple in its construction and arrangement, strong, durable, compact, thoroughly efficient in its use, readily installed with respect to a door and comparatively inexpensive to manufacture.

To the above ends essentially and to others which may hereinafter appear, the invention consists of the novel construction, combination and arrangement of parts as will be more specifically described and are as illustrated in the accompanying drawings wherein is shown an embodiment of the invention, but it is to be understood that changes, variations and modifications may be resorted to which fall within the scope of the invention as claimed.

In the drawings:

Figure 1 is an elevation of the lock, with one

side wall of the housing removed and showing the latching member and locking bolt in active position.

Figure 2 is a sectional plan illustrating the lock installed with respect to a door,

Figure 3 is a perspective view of the latching member,

Figure 4 is a section on line 4—4, Figure 1,

Figure 5 is a sectional plan illustrating the latching member in released position,

Figure 6 is a section on line 6—6, Figure 1,

Figure 7 is a fragmentary view in side elevation illustrating the locking bolt in released position, and

Figure 8 is a perspective view of the shifting device for the latching member.

The lock includes a housing or casing 1 formed of a horizontal top wall 2, a horizontal bottom wall 3, a vertical front wall 4, a vertical rear wall 5 and a vertical inner end wall 6. The housing 1 is open at its outer end. The walls 2, 3, 5 and 6 are integral with each other. The wall 4 is positioned against the edges of and is suitably connected with the walls 2, 3, 5 and 6. The height of the walls 4, 5 is materially greater than the width of the other of said walls.

Positioned against the open end of housing 1 is a combined closure and guide plate 7 which corresponds in width to that of the housing 1 and is of a length to extend above the wall 2 and to depend from the wall 3. The plate 7, as shown, acts as a closure for the open end of and also as a means for retaining housing 1 in pocket 8 formed in a door 9. The extended end terminal portions of plate 7 are to be mortised in the outer side edge of the door 9 and are to be secured to the latter by the holdfast devices, not shown, which are to be extended through the countersunk openings 10 formed in the plate. The latter also functions as a combined support and guide common to a latching member 11 and a locking bolt or member 12, to be referred to and for such purpose plate 7 is formed with an upper guide opening 13 for the passage of member 11 and a lower guide opening 14 for bolt 12.

The walls 4, 5 between the vertical median of housing 1 and wall 6 are formed with aligning openings 15, 16 respectively. The openings 15, 16 are located between the longitudinal median of housing 1 and wall 2. The door 9 is to be provided with a pair of aligned openings 17, 18 which align with the openings 15, 16 respectively. The door 9 has secured thereto, at opposite sides thereof, oppositely disposed bearing members 19, 20 formed with axial openings 21, 22 respectively

Integral with the inner face of wall 5 is a flat rectangular supporting lug 24 disposed in transverse relation with respect to housing 1 and formed at its free end with a socket 25 for the reception of a holdfast means, not shown, which is to extend through the wall 4. The length of lug 24 is such as to extend from the inner face of wall 5 to the inner face of wall 4. The lug 24 is of rectangular cross section and has its upper face disposed at the longitudinal median of housing 1. The lug 24 is arranged between the vertical median and open end of housing 1 and constitutes a combined support and guide for latching member 11.

Integral with the inner face of wall 5 is a flat rectangular supporting lug 29 disposed transversely of housing 1. The lug 29 is arranged below, aligns with and is spaced from the lug 24 and constitutes a combined support and guide for the member 12. The lug 24 further functions to arrest the bodily shifting upwardly of and for retaining member 12 on lug 29. The member 12 slides between the lugs 24 and 29.

The latching member 11 comprises a relatively short substantially rectangular bar-like body 30 having its outer end edge beveled as at 31. The body 30 is so constructed as to permit of its being disposed for use on either one of its lengthwise faces A or B. The side edges of body 30 are indicated at C, D. As shown body 30 is disposed on its face B. Integral with the face A of body 30 between the transverse median and outer end of the latter is a square lug 32 having its outer side face 32a flush with the side edge D of body 30. Integral with the face B of body 30 between its transverse median and outer end of the latter is a square lug 33 having its outer side face 33a flush with the side edge C of body 30. The body 30 in its faces A, B is formed with diagonal grooves. The grooves are indicated at 34, 35 and are of like form and align with each other. The side walls of each of the grooves are indicated at 36, 37 and disposed in parallel inclined plates. The grooves 34, 35 are arranged between the transverse median and inner end of body 30. The distance between the outer ends of the grooves and the inner end of the body 30 is greater than the distance between the inner ends of the grooves and the inner end of body 30.

Secured to the inner face of wall 6, as at 38, is an upstanding forwardly directed curved leaf spring 39 which permanently bears against the inner end 39a of body 30. The spring 39 acts to normally maintain member 11 in latching position. The member 11 is moved to released or non-latching position against the action of spring 39.

The lock includes a shifting device for sliding member 11 from latching to non-latching position. The said device consists of a vertically disposed actuating element 40 for and disposed at right angles to member 11 and a horizontally disposed slideable carrier 41 for element 40. The latter is formed of a rectangular head part or upper 42 and a frusto-tapered lower part 43 for actuating the member 11. The head part 42 is formed with an opening 44 and has each side vertically grooved as at 45, 46. The part 43 is integral with the bottom edge of part 42. The

part 43 is of less width and of less length than the width and length of the part 42.

The carrier 41 consists of a shaft 47 having a cylindrical intermediate portion 48, and a pair of reduced squared end portions 49, 50. The portion 48 slidably extends through the aligned openings 15, 16, 17, 18, 22, 23 and also through opening 44 of head part 42 of element 40. The latter is fixedly secured to shaft portion 48 centrally of the latter. The reduced end portions 49, 50 provide shaft 47 with a pair of peripheral shoulders 51, 52 against which abutment discs 53, 54 respectively are positioned. Secured upon the reduced end portions 49, 50 of shaft 47 are inner and outer socketed knobs 55, 56 respectively which clamp the discs 53, 54 against the shoulders 51, 52.

Engaging in one of the grooves 45, 46, as shown, the groove 45, is the rear free end of a flat controlling spring 57 for the slideable carrier. The forward end of spring 57 is anchored against a spacing collar 58 which is fixedly secured against the inner face of wall 5 by the holdfast means 59.

The lower part 43 of element 40 has its sides oppositely beveled as at 60, 61. One of said sides is for the purpose of riding against the wall 37 of one of the grooves 34 and with the inclination of such side being the same as that of the wall 37. As shown the side 61 of part 43 is positioned against the wall 37 of groove 34. The construction of the element 40 and member 11 permits of reversing them when desired. The disc 54 abuts one of the bosses 23 when the carrier is in inactive position and the disc 53 is to abut the other 23 when the carrier is shifted to active position. The normal position of the carrier is as shown in Figure 2 and is maintained in such position by the spring 57. The carrier is moved to active position against the action of spring 57. The normal position of the element 40 is as shown in Figure 2 with a beveled side of part 43 positioned against the end portion of a side wall of a groove in member 11. By pushing the carrier outwardly from the inner side of the door 45 the head element 40 will act on the member 11 and move it from latching to non-latching position. By pulling the carrier outwardly, the head element 40 will also provide for the shifting of member 11 to non-latching position. The slideable coaction of a beveled side of the actuating element 40 with the rear wall of a groove in the member 11, as the carrier is slid or pulled outwardly provides for the action as aforesaid.

The locking member 12 comprises a rectangular bar 62 disposed on its lower lengthwise edge and formed in proximity to its rear end with an enlarged groove 63 opening at the lower edge thereof. The groove 63 has a pair of straight side walls 64 and an arcuate top wall 65. Arranged in the groove 63 is a cam 66 formed eccentrically of its sides with stub shafts 67, 68 which are journaled in openings 69, 70 formed in the walls 4, 5 respectively. The cam 66 eccentrically thereof is formed with a socket 71 in the form of a die simulating a letter of the alphabet, or a number; as shown it is a letter.

The walls 4, 5 are provided with openings, not shown for the insertion of a key, not shown, formed to conform to the contour of the socket 70 to enter the latter for the purpose of rotating the cam in a direction to shift member 12 from the position shown in Figure 7 to locking position as shown in Figure 1.

The member 12 intermediate its ends and on 75

its upper face has formed integral therewith a square lug 72 which functions respectively for limiting the extent of the shifting of member 12 to non-locking position; to arrest the moving of member 11 to non-locking position when the member 12 is in locking position; and for limiting the extent of the shifting of member 11 to non-locking position when member 12 is in non-locking position. The lug 72 has its outer side face 73 flush with the side edge 74 of member 12. The lug 72 coacts with lug 24 for limiting the moving of member 12 to non-locking position. The lug 72 is arranged against lug 24 when member 12 is non-active. The lug 72 is arranged in the path of lug 32 or 33 depending upon the disposing of member 11 on its face A or B.

The member 11 is shifted to non-latching position for the purpose of unlatching the door when member 12 is in the position shown in Figure 7.

Any suitable form of keeper may be employed for the members 11, 12, when they are in latching and locking position respectively.

What I claim is:

1. In a lock, a horizontally disposed spring controlled normally active slidably mounted latching member formed in its top face with a groove disposed diagonally thereof, a slidable vertically disposed actuating element for said member formed of an apertured upper part having a side groove and lower part depending from the lower end of the upper part, and having an inclined side face for riding against a side wall of said diagonal groove to shift said member to inactive position, a controlling spring for said element, said spring being fixed at one end and having its other end positioned in the groove of said upper part, and a horizontally disposed slidably mounted push and pull carrier disposed at right angles to said member, said carrier extending through the aperture in said element being fixed, intermediate its ends to said upper part for bodily carrying said element on the push and pull movement of the carrier.

2. In a lock, a horizontally disposed spring controlled normally active slidably mounted latching member having its upper and lower faces each formed with a groove disposed diagonally thereof between its vertical median and rear end, said grooves being aligned and extending in the same direction, a slidable vertically disposed actuating element for said member formed of a vertically disposed apertured upper part provided at each side with a groove and a frusto-tapered lower part depending from the lower end of and of less width than said upper part, said lower part having its sides selectable for riding against a side wall of a selected diagonal groove to shift said member to inactive position, a controlling spring for said element, said spring being fixed at one end and having its other end positioned in a selective groove of said upper part, and a horizontally disposed slidably mounted push and pull carrier extending at right angles to said member, said carrier extending through the aperture in and being fixed, intermediate its ends, to said upper part for bodily carrying said element on the push and pull movement of the carrier.

3. In a lock, a horizontally disposed spring controlled normally active slidably mounted latching member having its upper and lower faces each formed with a groove disposed diagonally thereof between its vertical median and rear end, said grooves being aligned and extending in the same direction, a slidable vertically disposed actuating element for said member formed of a vertically disposed apertured upper part provided at each side with a groove and a frusto-tapered lower part depending from the lower end of and of less width than said upper part, said lower part having its sides selectable for riding against a side wall of a selected diagonal groove to shift said member to inactive position, a controlling spring for said element, said spring being fixed at one end and having its other end positioned in a selective groove of said upper part, and a horizontally disposed slidably mounted push and pull carrier extending at right angles to said member, said carrier extending through the aperture in and being fixed, intermediate its ends, to said upper part for bodily carrying said element on the push and pull movement of the carrier, supporting means common to said member, spring and carrier and having a part thereof providing an abutment, and said member being formed on its upper and lower faces with lugs between its vertical median and forward end for selective engagement with said abutment.

4. In a lock, a horizontally disposed spring controlled normally active slidably mounted latching member having its upper and lower faces each formed with a groove disposed diagonally thereof between its vertical median and rear end, said grooves being aligned and extending in the same direction, a slidable vertically disposed actuating element for said member formed of a vertically disposed apertured upper part provided at each side with a groove and a frusto-tapered lower part depending from the lower end of and of less width than said upper part, said lower part having its sides selectable for riding against a side wall of a selected diagonal groove to shift said member to inactive position, a controlling spring for said element, said spring being fixed at one end and having its other positioned in a selective groove of said upper part, and a horizontally disposed slidably mounted push and pull carrier extending at right angles to said member, said carrier extending through the aperture in and being fixed, intermediate its ends, to said upper part for bodily carrying said element on the push and pull movement of the carrier, supporting means common to said spring carrier and member, and a vertically disposed controlling spring for said member having its lower end fixed to said means and its upper end of curved contour permanently bearing against the inner end of said member.

5. A mechanism as set forth in claim 1 having combined therewith a supporting means common to said member, spring and carrier, and a vertically disposed controlling spring fixed at its lower end to said means, and having its upper end portion of curved contour permanently bearing against the inner end of said member.

STANLEY ZAGRZEJEWSKI.
